assignors to Andrew F. Wintercorn, Rockford, Ill.

Filed Feb. 6, 1964, Ser. No. 343,156

The portion of the term of the patent subsequent to
Mar. 3, 1981, has been disclaimed
1 Claim. (Cl. 209—29)

This invention relates to a new and improved method for separating ore particles, and is particularly concerned with improvements on what is disclosed in co-pending application, Ser. No. 63,167, filed Oct. 17, 1960, which resulted in Patent 3,123,551 on Mar. 3, 1964.

In accordance with this invention, an ore separator uses in combination the rotation of an inverted conical screen over which the ore is passed in crushed condition outwardly and upwardly by centrifugal force and opposed by the force of gravity for screening purposes, air duct means below the screen to blow out upwardly the fine dust particles into an exhaust hood above for their removal by suction, while the other particles of rock are more or less floated on the screen and allowed to discharge therefrom peripherally by centrifugal action, while the heavier particles of metal drop down through the screen and are collected and removed by means of suitable screws to a suitable receptacle, thereby obtaining with a dry method and with simple mechanism in a most efficient manner as good or better results than were obtainable heretofore only by wet methods.

The ore separator used with this method is easily adjusted to suit the different requirements presented by different ores. Thus:

- (1) The pressure and volume of air is variable to suit different requirements;
- (2) The speed of the screen disk may be varied and also the inclination thereof to suit different requirements;
- (3) The rotary screen disk may be varied in diameter to suit different requirements; and
- (4) The fineness of the screen may be varied to suit different requirements.

The invention is illustrated in the accompanying drawing, in which:

FIG. 1 is a central vertical section through an ore separator used in practicing the method of this invention;

FIG. 2 is a fragmentary plan view taken on the line 2—2 of FIG. 1;

FIG. 3 is a sectional detail on the line 3—3 of FIG. 2, and

FIG. 4 is a fragmentary sectional detail corresponding to a portion of FIG. 1, showing a modified or alternative construction.

Similar reference numerals are applied to corresponding parts in these four views.

Referring first to FIGS. 1 to 3, the reference numeral 5 designates a variable speed electrical motor, the armature shaft 6 of which carries a worm 7 transmitting drive to a worm gear 8 to drive a central vertical shaft 9 continuously in a clockwise direction, as viewed from above, and accordingly turn an inverted generally conical screen 10 with respect to the open tops of a plurality of funnels 11 arranged in a circle under the screen with their upper ends covering substantially the complete bottom area thereof. The funnels 11 have discharge tubes 12 extending from the bottom thereof to conduct screened ore particles indicated at 13 to a suitable receptacle or conveyor, it being anticipated that this portion of the screened ore heavy enough to drop through the screen 10 but not heavy enough to drop into the air duct funnels 14 against upwardly discharging air 15 is worth retrieving and subjecting to further crushing to release the

2

metal particles which would doubtlessly be caught in the funnels 14 on the next pass through the machine. The metal particles are indicated at 16. Air under pressure is delivered to the lower portion of the funnels 14 through conduits 17, and metal particles 16 collected in the bottom of the funnels 14 are conveyed away to suitable receptacles or conveyors by power-operated screws 18.

The crushed ore indicated at 19 is delivered to the ore separator into a hopper 20 which has a discharge down-spout 21 extending downwardly therefrom terminating in a flared lower end 22 in a predetermined elevated concentric relationship to a conical cap 23 secured to the upper end of the shaft 9 in elevated relationship to the annular drive flange 24 to which the inner ends of the triangular sections 25 of the screen 10 are secured, as indicated at 26. The crushed ore 19 flows by gravity under a predetermined head depending upon the length of the down-spout 21 and elevation of the hopper 20, and is fairly uniformly distributed on the screen 10 around the cap 23, and from this point on the crushed ore flows outwardly by centrifugal force due to the rotation of screen 10, and, of course, in its outward travel the ore is gradually spread out more and more, as indicated by the curved dot and dash line 27 on both sides of FIG. 1. In this spreading out of the crushed ore fine dust particles, indicated at 28, will immediately be blown upwardly by the air 15 and collected in a conical hood 29 disposed over the ore separator in concentric relationship to the screen 10 and be carried away through dust exhaust conduits 30 by suction fans, as indicated by the arrows 31. The metal particles 16 being heavier will drop through the screen 10 into funnels 14, and there is ample opportunity for these metal particles to be separated in this way because, as shown in FIG. 1, the funnels 14 cover the major portion of the area of the underside of the screen 10. Any larger crushed ore particles, too light to drop through the screen 10 against the upward flow of air, even though small enough to pass through the screen, but heavier than other particles of the same size, on account of mineral 40 locked therein, will have an opportunity to drop through, as indicated at 13, into funnels 11 to be collected for further processing to retrieve the mineral particles therein, but the remaining crushed ore particles, indicated at 32, leaving the marginal edge portion of the screen 10 are lighter than the particles 13 and contain little or no ore particles or are too large to pass through the screen 10, and will be discharged onto an annular ledge 33 that slopes downwardly for discharge of these crushed ore particles into an annular gutter 34 in which a suitable number of 45 paddles 35, turning with the screen 10, are arranged to operate to discharge the crushed ore through openings 36 at one point onto a suitable conveyor 37 to carry this crushed ore away to a refuse heap to be hauled away, unless tests reveal any likelihood of this ore being worth 50 further crushing for reprocessing in the manner described, similarly as in the case of the particles 13, previously mentioned.

Rollers 38 are mounted on the outer ends of L-shaped arms 39 secured to the outer ends of segments 25 of the screen 10 to support the screen 10 at a predetermined elevation at circumferentially spaced points around the periphery thereof by rolling contact of rollers 38 in an annular track 40 which in turn is adjustable in elevation with respect to the base 41, the track 40 having a plurality 65 of circumferentially spaced jack screws 42 extending downwardly therefrom freely through holes 43 in posts 44 and having nuts 45 threaded thereon and engaging the tops of the posts 44 and arranged to be adjusted by hand to increase or decrease the slope of the screen 10. The annular ledge 33, previously mentioned, is mounted on and 70 adjusts up and down with the annular track 40. The paddles 35, previously mentioned, are hingedly connected as

at 46 with the peripheral edge portion of the screen 10 so that a slight change in elevation of the screen will not affect the operation of these paddles in the annular gutter 34. The sections 25 of the screen 10 are flexibly connected by tapered gusset strips of neoprene or other suitable material, indicated at 47, whereby to compensate for the change in width of the gaps between the sections as the screen 10 is adjusted upwardly or downwardly at the periphery.

In the other figure, FIG. 4, the funnel 11a corresponds to funnel 11, and there are three inner funnels 14a, 14b and 14c shown inside the funnel 11a, each with its own separate power-operated screw 18' in the bottom thereof to carry away the metal particles collected in these funnels, and each having its own separate air delivery tubes, as indicated at 17a, 17b and 17c, respectively, so that the air pressure and amount of air discharge is greatest at 15a, not as high at 15b, and least at 15c, whereby to have the most effective air blast through the thickest layer of crushed ore immediately around the cap 23 at the center of the screen 10', less air at an intermediate thickness about half way out from the center and still less air farther out. That should insure more efficient removal of the fine dust and dirt particles 28 and more efficient sifting out from the crushed ore of the heavier metal particles 16, regardless of the difference in this thickness of the crushed ore on the screen 10' at the different levels. In other words, the air pressure and volume at 15b can be approximately equal to that at 15 in FIG. 1, but by increasing the pressure and volume at 15a, the efficiency of the machine should be greatly increased, and likewise by decreasing the volume and pressure at 15c relative to that at 15b.

In operation, therefore, it should be clear from the foregoing description that with this improved method one is enabled to accomplish with a dry method what it was possible to accomplish heretofore only with a wet method, the air blast or blasts serving to float the ore in its crushed condition as it is sifted, so that the heavier metal particles can be separated out and the lighter rock particles are discharged peripherally of the screen as it turns, using centrifugal force. The inverted conical screen increases efficiency of ore separation as it affords a better opportunity for metal particles to drop through the openings than where the reverse inclination is provided, as in my co-pending application, the reason being that the far side of each opening is higher, the analogy in golf to putting on an inclined green from below the hole (as here) as against putting from above the hole (as in the other case) making this advantage quite clear. Also, with the present novel

arrangement, gravity is utilized to the best possible advantage to separate out the small metal particles or small ore particles containing a good amount of metal. There is also better regulation possible with the present invention, 5 because it is a simple matter to vary the speed of rotation of the screen, centrifugal force being relied upon solely to move the material outwardly and upwardly over the screen, gravity acting always in the opposite direction during the separation of the metal particles from the ore 10 particles.

It is believed the foregoing description conveys a good understanding of the objects and advantages of this invention. The appended claim has been drawn to cover all legitimate modifications and adaptations.

15 What is claimed is:

The method of ore separation which consists in continuously delivering in a vertical substantially cylindrical stream finely crushed ore containing free metal particles centrally on top of an inverted generally conical screen 20 that is of large diameter in relation to the cylindrical stream, turning the screen on a vertical axis at a speed bearing such relation to the rate of delivery of the crushed ore that this material flowing outwardly and upwardly by centrifugal force and opposed by gravitational force is 25 spread out in a fairly uniform thin layer of gradually diminishing depth toward the rim of said screen, the holes in the screen being large enough to allow dropping therethrough of metal particles in the ore, continuously delivering air under pressure upwardly through the holes in the 30 screen to blow upwardly the smaller ore particles as dust while floating the larger ore particles relative to the screen on the air streams to prevent their dropping through the holes while allowing the metal particles by virtue of their greater weight to drop through said holes, collecting the 35 metal particles that drop through the screen, conducting away the smaller ore particles that are blown upwardly as dust from the screen, and separately collecting the larger ore particles which after being floated outwardly over the screen drop by gravity from the rim thereof.
